The ornamental design for an air delivery tube with cuff, as shown and described.

DESCRIPTION

FIG. 1 is a front perspective view of an air delivery tube with cuff according to a first embodiment showing our new ornamental design;

FIG. 2 is a rear perspective view thereof;

FIG. 3 is a top view thereof;

FIG. 4 is a front view thereof;

FIG. 5 is a right side view thereof;

FIG. 6 is a left side view thereof;

FIG. 7 is a front perspective view of an air delivery tube with cuff according to a second embodiment showing our new ornamental design;

FIG. 8 is a rear perspective view thereof;

FIG. 9 is a top view thereof;

FIG. 10 is a front view thereof;

FIG. 11 is a right side view thereof; and,

FIG. 12 is a left side view thereof.

The broken lines shown in FIGS. 1-12 illustrate portions of the air delivery tube with cuff that form no part of the claimed design.

The dotted lines represent the boundary between claimed and unclaimed portions of the design, and do not form a part of the claimed design.
